UNITED STATES PATENT OFFICE.

HARRY EDWARD COATES, OF SACRAMENTO, CALIFORNIA.

TOY FORT.

1,348,086.

Specification of Letters Patent. Patented July 27, 1920.

Application filed November 20, 1919. Serial No. 339,409.

To all whom it may concern:

Be it known that I, HARRY E. COATES, a citizen of the United States, and a resident of Sacramento, in the county of Sacramento and State of California, have invented a new and Improved Toy Fort, of which the following is a description.

My invention relates to a toy fort and more particularly to a toy fort on which a gun is mounted and from which a figure representing a gunner is adapted to emerge upon the tripping of a trigger controlling the mechanism, the arrangement being such that as the figure emerges the gun will be automatically fired to give the effect of having been fired by the gunner previously concealed in the fort.

Objects of the invention are to provide means to insure the emergence of the figure and the firing of the gun; to provide a gun of the type in which a plug is forced out under the pressure due to the forward movement of the plunger to produce a sound simulating an explosion; and to time the release of the plunger with the emerging of the figure.

More specific objects of the invention are to provide novel and convenient means for the ready setting of the gun plunger and for the tripping of the trigger, the trigger control providing for releasing the same either by a pull on the string at the rear of the fort or by the impact of a ball or other projectile against the trigger at the front of the fort.

Reference is to be had to the accompanying drawings forming a part of this specification, it being understood that the drawings are merely illustrative of one example of the invention.

Figure 1 is a side elevation of a toy fort embodying my invention with a figure representing a gunner concealed within the fort;

Fig. 2 is a perspective view with the figure in the emerged position and the gun plunger released about to move forwardly to discharge or dislodge the plug;

Fig. 3 is a longitudinal vertical section of the toy fort with the figure concealed and the mechanism set;

Fig. 4 is a plan view with the parts in the positions shown in Fig. 3, portions being broken away and others in section.

In carrying out my invention in practice a box-like structure 10 is provided which is

given an appearance to simulate a fort. On the fort, at the front, is mounted a gun 11 and a vertically swingable figure 12 is mounted to be swung to a position below the top of the fort within the latter or to emerge. The gun is of that type in which a cork or like plug 13 closes the muzzle of the gun and fits tightly to require a force to dislodge it. Usually the plug will be secured to one end of a string 14 of suitable length, the opposite end of the string being fixedly secured as at 15 to any fixed part of the structure.

The figure 12 will ordinarily represent a gunner and it is mounted on a transverse rockable shaft 16. A torsion spring 17 coiled about the shaft is secured at one end to the figure and secured at its opposite end to any fixed portion of the structure, whereby in the lowering of the figure to approximately the horizontal position shown in Fig. 3 to be concealed within the fort, the spring will be placed under tension and will serve, upon release of the figure, to throw the latter through an angle to project it through the top of the fort to extend above the latter in the rear of the gun as if manning the latter. In the lowered position the figure is restrained by a trigger 20 which is provided with a notch 19 adapted to receive a transverse bar 18 or like element on the figure, said bar being represented as carried by the hands of the figure in the illustrated example. The trigger is in the form of an elongated rod or bar having guided movement in a keeper 21 in the bottom of the fort.

In the gun a plunger 22 is movable and provided with a head 23 snugly fitting the barrel, a compression spring 24 normally tending to force the plunger forwardly. Said plunger extends through the breech of the gun and has a forwardly facing shoulder 25, the plunger being permitted sufficient vertical play for the shoulder 25 to engage the rear end of the gun, whereby to restrain the plunger from forward movement with the spring 24 under compression. The rear end of the plunger is enlarged as at 26 in any suitable form to limit the forward movement of the plunger under the action of the spring. In order to provide a convenient means for the ready setting of the plunger with the spring under compression, I employ a lever 27 fulcrumed at its lower end as at 28 by any suitable means on the bottom of the fort, and at its upper

end through the top of the fort through any suitable slot or opening provided for the purpose. The lever, when the plunger is in the rearward position, rests against a lateral projection 29 on the plunger, whereby in the forward movement of the latter the lever will be carried forwardly in position to retract the plunger when the lever is thrown rearwardly.

10 The trigger is spring-pressed in a manner normally to retain its engagement with the bar 18 of the figure to restrain the latter, any suitable spring being provided for the purpose. In the illustrated form a plate spring 15 30 is secured to a block 31 or the like, on the bottom of the fort and engages at its opposite end against a pin 32 or the like on the trigger 20, so that when the trigger is engaged with the bar 18 the spring 30 will be placed under tension. Means may be provided for variously tripping the trigger. In the preferred form of my invention, the forward end of the trigger extends through the front of the fort and is provided with 25 a target 33 in the form of a disk which is adapted to receive the impact of a ball 34 or like projectile to give a rearward movement to the trigger to release the bar 18. In order to operate the trigger from the rear 30 of the fort, a spring 35 is connected at one end to the trigger and extends to the back of the fort where it is provided with a ball 36 or other finger-hold to exert a pull on the string. The trigger head is beveled above 35 the notch 19 to cause the automatic setting of the trigger by the lowering of the figure 12.

The top of the fort for a large portion thereof, as indicated at 10^a, is fixed while a 40 cover or trap door 10^b is disposed over the figure 12, covering the same, and is hinged as at 10^c to freely rise with the upward pressure of the figure against said door. From the above description it will be seen 45 that with the plunger of the gun set by the lever 27 as in Fig. 3, with the trigger to be tripped either by impact against the disk 33 or by a pull on the string 35, the figure will throw the door through an angle of 180° 50 to lie on the top of the fort, the figure emerging through the opening, and as the figure approaches the upright position in the rear of the gun, the arm 18 or other predetermined member moving with the figure 55 will engage the gun plunger 22 to disengage its shoulder 25 and permit the spring 24 to throw the plunger forwardly, thereby compressing the air within the gun barrel in the rear of the plug 13 to dislodge the 60 latter.

I would state in conclusion that while the illustrated example constitutes a practical embodiment of my invention, I do not limit myself strictly to the mechanical details 65 herein illustrated, since manifestly the same

can be considerably varied without departure from the spirit of the invention as defined in the appended claims.

Having thus described my invention, I claim as new, and desire to secure by Letters Patent:

1. A toy fort including a structure, a gun mounted thereon, a figure movably mounted to be given a position below the top of the fort to be concealed or to emerge therefrom 75 to simulate a gunner manning the gun, means to move said figure to the emerged position, means to cause the discharge of the gun with the emergence of the figure, and means to restrain or release the figure. 80

2. A toy fort including a hollow structure, a gun mounted thereon, a figure swingably mounted at the rear of the gun to assume a lowered position within the fort or a raised position adjacent to the gun, spring 85 means tending to swing the figure to the raised position, a hinged door adapted to overlie the figure in the lowered position and to be raised by the figure with the swinging of the latter, means operable by 90 the figure to cause the discharge of the gun, and a trigger adapted to restrain said figure in the lowered position or to release the figure.

3. A toy fort including a hollow structure, 95 a gun mounted thereon, a figure swingably mounted at the rear of the gun to assume a lowered position within the fort or a raised position adjacent to the gun, spring means tending to swing the figure to the 100 raised position, a spring-pressed plunger operating in the gun and adapted to be held in the retracted position with the spring under compression, means on the figure adapted to trip the gun plunger with the rising of the figure, and trigger-controlled means to restrain the figure or to release the same. 105

4. A toy fort including a hollow structure, a gun mounted thereon, a figure swingably mounted at the rear of the gun to assume a lowered position within the fort or a raised position adjacent to the gun, means tending to swing the figure to the raised position, a spring-pressed plunger extending 110 into the gun and adapted to be restrained in the retracted position with the spring under spring pressure, manually operable means to retract the plunger, means to release the plunger by said figure, and means to restrain the figure against upward movement or to release the same. 115

5. In a toy fort, a figure swingable from a lowered to a raised position, means tending to swing the figure to a raised position, 125 a trigger slideable longitudinally of the fort and adapted to engage said figure in the lowered position to restrain the same against upward movement, said trigger extending through the front of the fort, and a target 130

on the front of the trigger adapted to receive the impact of a projectile for releasing the figure.

6. In a toy fort, a figure swingable from a lowered to a raised position, means tending to swing the figure to a raised position, a trigger slidable longitudinally of the fort and adapted to engage said figure in the lowered position to restrain the same against

upward movement, said trigger extending 10 through the front of the fort, and a target on the front of the trigger adapted to receive the impact of a projectile for releasing the figure; together with a pull-string attached to the trigger and extending rearwardly through the rear end of the fort. 15

HARRY EDWARD COATES.
